US00D783640S

(12) **United States Design Patent** (10) Patent No.: **US D783,640 S**
(45) Date of Patent: **** Apr. 11, 2017**

(54) **DISPLAY SCREEN OR PORTION THEREOF
WITH GRAPHICAL USER INTERFACE**

6,897,880 B2 5/2005 Samra
D513,511 S 1/2006 Decombe
D523,442 S 6/2006 Hiramatsu

(71) Applicant: **Apple Inc.**, Cupertino, CA (US)

(Continued)

(72) Inventors: **Greg Apodaca**, Mountain View, CA (US); **Imran Chaudhri**, San Francisco, CA (US); **Tiffany Jon**, Sunnyvale, CA (US)

FOREIGN PATENT DOCUMENTS

CN 303181278 4/2015
CN 303368352 9/2015

(Continued)

(73) Assignee: **Apple Inc.**, Cupertino, CA (US)

(**) Term: **15 Years**

(21) Appl. No.: **29/576,134**

(22) Filed: **Aug. 31, 2016**

Related U.S. Application Data

(63) Continuation of application No. 29/484,349, filed on Mar. 7, 2014, now Pat. No. Des. 766,318.

Primary Examiner — Darlington Ly

Assistant Examiner — Daniel J Domino

(51) **LOC (10) Cl. 14-04**

(74) Attorney, Agent, or Firm — Sterne, Kessler, Goldstein & Fox P.L.L.C.
